SPARK PLUG

Louis H. Crook, Washington, D. C.

Application December 9, 1943, Serial No. 513,561

8 Claims. (Cl. 123—169)

1

This invention relates to spark plugs, either radio shielded or unshielded, for internal combustion engines.

One of the principal objects of the invention is to improve the electrical, thermal, and mechanical features of a spark plug, thereby to increase the overall efficiency, and enable it satisfactorily to meet the increasing requirements of temperature and pressure conditions of the modern internal combustion engine.

Another important object of the invention is to provide a spark plug in which overheating is prevented by insulating the plug where it is directly subjected to the influence of the hot gases of the combustion chamber of the engine.

A further object is to provide a spark plug in which the electrodes are protected, by suitable insulating means, from excessive heating, thus preventing pre-ignition and prolonging the life of the electrodes.

A further object is to provide a spark plug in which injury to the dielectric of the main body of the plug, as well as the dielectric of the adjacent cable in the case of a shielded spark plug, by overheating of the plug, is prevented.

A further object is to provide a spark plug which may be very small in diameter so as to be used safely in engines having high temperature and pressure requirements.

My invention accordingly consists in the features of construction and composition of the members and in the relative proportioning and disposition thereof, all as more completely outlined herein.

To enable others skilled in the art fully to comprehend the underlying features of this invention and the modifications in structure and relation contemplated thereby, drawings depicting several of the various possible embodiments of the invention have been annexed as part of this disclosure, and in such drawings like characters of reference denote corresponding parts throughout all of the views, in which

Fig. 1 is a detail view showing the barrel or outer electrode of a preferred form of my invention housing the inner electrode and dielectric of the plug.

Figs. 2, 3, and 4 are end views of various forms of barrel.

Figs. 5 and 6 are cross-sectional views of two forms of the invention.

This spark plug comprises a core 12 the dielectric of which may be of insulating material such as mica or porcelain such as in common use in most spark plugs and through the center of which

2

core passes one electrode 13 adapted to be connected in any suitable manner with the source of electric power.

Surrounding the core 12 is a thin metal barrel 8 which in the present instance comprises a tubular member 14 preferably of electrode metal, or of other suitable highly conductive material both as to heat and electricity, which is screw threaded for a considerable distance as indicated at 15. 10 This barrel when made of electrode metal, terminates at its lower end in a plurality of electric terminals 16 which may be homogeneous with the metal of the barrel. The barrel, however, may be made of a non-electrode metal with the 15 electrodes of a suitable electrode material welded to the lower end thereof. It is advantageous, however, to avoid the use of welded joints, which tend to impede the free flow of heat. These terminals or electrodes 16 coat with the center electrode 13 in the customary manner.

Surrounding the lower part of the barrel 14 is a sleeve of heat insulating material.

In assembling the parts the dielectric 12 and center electrode 13 are positioned within the barrel 14 by the usual factory methods. In the modifications shown in Figs. 3 and 4, the barrel 14' in Fig. 3 is provided with four electrodes 16, and the barrel 14'' in Fig. 4 is provided with one such electrode.

30 In the modification shown in Fig. 6 the heat insulating ceramic material 25 is cast between a metal shell 26 and the metal barrel 14 of an unshielded plug, the threads 15 on the barrel and hollow-shaped portion of the shell at 33 serving as lugs to hold the various members in fixed relation to one another. In case the barrel is desired detachable from the ceramic 25 the threads 15 serve as accurate screw threads for screwing the barrel into the ceramic, and in such cases it 40 is preferable to provide a metal lock nut as shown at 40 in Fig. 5.

The metal shell 26 in Fig. 6 serves as a means for strengthening the enclosed ceramic material, and a means for providing the screw-threaded 45 portion at 39 to engage with the cylinder wall. At the same time it provides heat radiating fins 36. The portion of the barrel exposed to direct action of the hot gases is made as small as possible in keeping with the electrical requirements and protects as much as possible from the radiation and conduction of the hot gases by extending the heat insulating material and metal shell over the outer electrodes as shown at 35 and 41, respectively.

The metal extension 41 in Fig. 6 carries the

heat toward the metal of the cylinder block and the heat is radiated to the atmosphere by means of the fins 36. Thus, a very large percentage of the lower area of the normal spark plug in contact with the hot gases, does not in this invention directly contact the metal of the electrodes.

In the modification in Fig. 5 and here shown applied to a radio shielded plug, the heat insulating material constitutes the large part of the plug. Means for locking the barrel 14 into the shell 26 is here shown as a screw thread with lock nut 40. The shell 26 is formed as a hexnut preferably finned for radiating purposes, and screw threaded at 39 for engagement with the cylinder block. The lower portion of this shell adjacent to the electrode points is preferably shaped or streamlined as shown at 29 to allow a smoother flow of the compressed gases and at the same time protect as much as possible the electrodes from the direct and intense radiant heat from the hot gases.

In all cases where the heat insulation means is applied to an unshielded spark plug a small metal rod, as indicated at 43 in Fig. 6, is inserted through the insulation at a point near the outer electrodes and embedded therein so as to ground the spark plug to the cylinder block and permit the ready flow of the ignition current through the engine. There is no necessity for this in a shielded plug, the return being by way of the shield of the ignition system, of which the shield of the spark plug forms a part.

The word "ceramic" used herein is to be understood as embracing such porcelains and the like which are molded and baked under high temperature conditions and which have a high degree of heat resistance and a coefficient of expansion approximately the same as the adjacent metal. While such materials, as well as mica also mentioned herein, are also electrical insulators as well as heat insulators, that feature may be disregarded insofar as my shielded spark plug is concerned, for repeated tests have proved that no current will flow from the spark plug to the engine block in a completely shielded ignition system in which this plug is especially adapted to be used, i. e., in a shielded system as shown and described in my prior United States Patent No. 1,645,643, dated October 18, 1927. In the case of an unshielded plug, however, special means for grounding the plug to the engine block, so as to insure the free flow of the return current through the engine should be used, as explained above.

It will be apparent that the heat insulating feature of my invention consists primarily of materially reducing the amount of metal of a spark plug which is exposed to the direct action of the hot gases of the combustion chamber of the engine. Where the portion of the spark plug entering the cylinder wall consists entirely of insulating material, only a small part of metal, being that of the electrodes within the firing chamber of the spark plug, is so exposed. Where a metallic sleeve or shell surrounds the insulating material, the metal thereof is also exposed, but this has little effect in the way of heating up the spark plug proper since it is insulated therefrom. Thus, protection to the spark plug as a whole is provided against excessive heating due to radiation, conduction and convection from the hot gases as they pass back and forth through the interstices of the lower portion of the plug.

While the application of my invention for heat insulating a shielded spark plug is shown in the

drawings as applied to a spark plug in which the shield is in the form of a cylinder which is an integral part of the spark plug proper, it will be apparent that this feature may be incorporated also in a shielded spark plug in which the shield is in the form of a cap or dome crimped or otherwise held to the body of a completed and otherwise unshielded spark plug, such, for example, as is shown in my Canadian Patent No. 294,403, dated November 5, 1929.

The invention is of simple and practical construction and may be easily and inexpensively manufactured, assembled and installed without modification of any of the parts of the engine itself as now in use.

Likewise, while keeping the dimensions of the barrel or main body of the plug more or less standard, my spark plug can be readily adapted to meet the particular temperature requirements of different engines by merely attaching to the barrel of the plug the heat insulating and radiating members of appropriate types and dimensions as described above.

While the invention has been described in accordance with the preferred embodiments, it is apparent that many variations and modifications may be resorted to without departing from the scope of equivalents within the purview and spirit of this invention as defined in the following claims.

I claim:

1. A spark plug adapted to be inserted into an engine block including a central part with co-operating electrodes, and a sleeve of heat insulating material between the central part and the walls of the opening in the engine block in which the plug is inserted, said sleeve projecting beyond and partly covering said electrodes at their outer ends to protect them from gaseous products of combustion within the engine.

2. In a spark plug for combustion engines having metal electrodes, the combination of a metal shell externally threaded to engage the usual spark plug opening in the engine block, and means interposed between the shell and adjacent portions of the spark plug surrounding and partly enclosing the exposed ends of the electrodes to reduce the radiation of heat from the engine gases thereto, said means being of a heat insulating material adapted to withstand high temperatures.

3. A spark plug as set forth in claim 2 including means providing electrical contact with the engine through the heat insulating material.

4. In an unshielded spark plug having a barrel portion and electrodes, an exteriorly threaded metal shell to engage the threaded opening of an engine cylinder, heat insulating material interposed between the shell and adjacent portions of the spark plug, and means providing electrical contact of the barrel of the plug with the engine, said means consisting of a metal member embedded in the insulating material at a point near the outer electrodes and contacting the barrel of the plug and the shell.

5. A spark plug as set forth in claim 4 in which the metal member contacts the barrel of the plug and the wall of the engine.

6. A spark plug especially adapted for use in shielded ignition systems comprising, in combination, a barrel of electrically conductive material having a core, an electrode therein, said barrel terminating in at least one electrode, a ceramic member surrounding said barrel at its lower end, the lower portion of said member being exteriorly threaded to engage the threaded opening of an

engine cylinder and the upper portion terminating in a nut for screwing the plug in and out of the cylinder, and a lock nut in threaded engagement with the barrel and positioned above the said ceramic member.

7. In a spark plug having a hollow metallic body, an electrode within the body, a dielectric material between the electrode and the body, and a heat insulating material on the outside of the body surrounding and partly enclosing the exposed end of said electrode and adjacent portion of said body.

8. In a spark plug having a hollow metallic casing, an electrode within the casing, a dielectric material between the electrode and the casing, an exteriorly threaded metallic shell, and a heat insulating material between the casing and the shell surrounding and partly enclosing the exposed end of said electrode and casing, said shell protecting the exposed end of said heat insulating material.
